(57) **CLAIM**

The ornamental design for a toilet plunger and holder, as shown and described.

DESCRIPTION

FIG. 1 is a perspective view of a first embodiment of a toilet plunger and holder showing our new design;

FIG. 2 is a front view thereof;

FIG. 3 is a rear view thereof;

FIG. 4 is right side view thereof; the side opposite being a mirror image thereof;

FIG. 5 is a top plan view thereof; and

FIG. 6 is a bottom plan view thereof.

FIG. 7 is a perspective view of a second embodiment showing contrasting materials with the use of stippling;

FIG. 8 is a front view thereof;

FIG. 9 is a rear view thereof;

FIG. 10 is a right side view thereof; the side opposite being a mirror image thereof;

FIG. 11 is a top plan view thereof; and,

FIG. 12 is a bottom plan view thereof.
